(57) **CLAIM**

The ornamental design for a cooling device for neck, as shown and described.

DESCRIPTION

FIG. 1 is a perspective view of a cooling device for neck showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the cooling device for neck where the cooling device for neck is in a fully open state;

FIG. 10 is a front elevational view thereof; and,

FIG. 11 is a perspective view of the cooling device for neck where the cooling device for neck is in a configuration of use.

The broken lines immediately adjacent to the shaded areas depict the bounds of the claimed design, while all other broken lines are directed to environment. The broken lines form no part of the claimed design.
